REFRIGERATING APPARATUS

Anthony T. Stock, Muskegon, Mich., assignor
to The Brunswick-Balke-Collender Company,
Chicago, Ill., a corporation of Delaware

Application March 7, 1935, Serial No. 9,704

4 Claims. (Cl. 62—127)

This invention relates to refrigerating apparatus and more particularly concerns improvements in expansion and evaporating mechanisms for refrigerating systems.

In refrigerating systems, and particularly those of the type used to cool fluids, such as drinking water and other beverages which are subject to continuous or intermittent draft, it is desirable that the refrigerant in liquid form be evaporated in direct heat exchanging contact with the coils carrying the fluids to be cooled. It is further desirable that the temperature to which the draft liquid is cooled be held within reasonable limits by automatic control mechanism. In many installations, such as fountain, bar or counter coolers, it is essential that the cooling apparatus occupy a relatively small space.

With the above and other considerations in mind, it is the object of the present invention to provide a refrigerating system embodying improved compact and unitary expansion and evaporating mechanism, together with improved control means for governing the supply of refrigerant to the evaporating chamber. A particular object of the invention is the provision of an evaporator, an expansion valve and control means therefor which constitute a single unitary structure combining the advantages of direct evaporation of the liquid refrigerant on the body or surface to be cooled with accurate and automatic control of the temperature of the cooled body or surface. The improved evaporating and expansion mechanism is particularly applicable to beverage coolers, but the invention, in its broader aspects, is not limited to this application.

In general, the above and other objects of the invention are carried out by providing a suitable evaporator chamber and by locating therein an expansion valve which controls the flow of liquefied refrigerant to the evaporator chamber and further directs the refrigerant in the form of liquid streams or sprays into contact with the beverage cooling coil or other body or surface to be cooled. The expansion valve is automatically controlled in accordance with the temperature of the evaporator chamber or of the liquid, surface or body to be cooled, and in a preferred form of the invention, the valve mechanism is so constructed and arranged that the flow of liquid refrigerant aids in properly closing the valve when the required amount of liquid refrigerant has been admitted to the evaporator chamber. The opening and closing of the expansion valve is preferably effected by a diaphragm or equiva-

lent expansible means actuated by changes in the pressure of a thermally expansible fluid. The pressure chamber including the diaphragm or equivalent means is connected through a suitable duct to a bulb or equivalent means responsive to the temperature of the draft liquid or other surface or body to be cooled or to the temperature of the evaporator chamber. In accordance with the invention, although the expansion valve mechanism proper is disposed within the evaporator chamber, the pressure chamber within which the thermally expansible fluid acts upon the valve operated diaphragm or equivalent means is located outside of the evaporator chamber at some point where temperatures appreciably higher than those of the evaporator chamber prevail. Due to the location of the expansion valve in the evaporator chamber, direct expansion of the liquid refrigerant into contact with the body to be cooled is conveniently obtained in a very compact structure, while at the same time, the isolation of the expansion valve operating pressure chamber from the evaporator chamber prevents erratic operation of the expansion valve control means.

The invention will be best understood by reference to the accompanying drawings in which certain embodiments thereof have been illustrated. In the drawings:

Figure 1 is a diagrammatic elevation of a refrigerating system embodying the invention, certain parts being shown in section to disclose the interior construction thereof;

Figure 2 is an enlarged sectional view of the expansion valve mechanism shown in Figure 1;

Figure 3 is an enlarged plan view of the temperature responsive bulb of the system; and

Figure 4 is a partial sectional view of a modified form of expansion valve operating means.

Referring to the drawings, and more particularly to Figure 1, the system there disclosed as embodying my invention comprises generally a refrigerant compressing and condensing unit C and an evaporator chamber or low-side E. The refrigerant compressing and condensing unit may take any suitable known form, and as shown, comprises a compressor 5 driven by a motor 6 and connected to discharge compressed refrigerant into a condenser 7. The intake 8 of the compressor 5 is connected to the suction line 9 from the evaporator E, and the outlet 10 of the compressor is connected to the inlet of the condenser 7 through the pipe 13. The outlet of the condenser 7 is connected through a liquid

collecting chamber 11 to the refrigerant supply line 12 leading back to the evaporator E.

The compressor of the unit C preferably operates intermittently and may be automatically started and stopped by any suitable control means responsive to the temperature of or pressure within the evaporator E or the pressure within the suction line 9. In the disclosed embodiment, a pressure operated switch S, connected to the suction line 9, is employed to control the operation of the compressor driving motor 6. This switch acts in a manner known in the art to close the circuit between the motor 6 and a source of electric power 14 when the pressure in the suction line 9 rises above a predetermined value, and to open this circuit and so stop the compressor when this pressure drops below a predetermined value. The switch S may also be arranged to open the motor circuit if for any reason a dangerous or excessive pressure is built up by the compressor and to this end, a pressure connection 15 is provided between the compressor outlet 10 and the switch S.

The above described refrigerant compressing and condensing unit C operates in the usual and well known manner, drawing gaseous refrigerant from the suction line 9, compressing it in the compressor 5 and cooling and liquefying the compressed gas in the condenser 7. The liquefied refrigerant collects in the chamber 11 and passes through the pipe 12 to the evaporator E.

The evaporator chamber E may take any suitable form, and as shown, may comprise a vertically disposed chamber of cylindrical section having upper and lower end walls 16 and 17. In the disclosed embodiment, the evaporator is employed to cool a liquid subject to draft, and accordingly, a coil O is disposed in the evaporator chamber E through which the liquid to be cooled passes. The ends of the coil O pass through sealed openings in the wall 17 of the chamber, and the inlet end 19 thereof is connected to the source of liquid to be cooled, which may be a beverage reservoir or the mains of a drinking water supply system. The outlet end 20 of the coil O is provided with a tap or faucet 21 for controlling the draft of cooled liquid. The coil O shown in the disclosed embodiment comprises a plurality of vertical cylindrical sections 22 and 23, and the liquid passes upwardly through the outer section 22 and downwardly through the inner section 23. A hollow central core or baffle 24 is suitably supported within the inner coil section 23 and is provided with an outwardly inclined inwardly extending flange 25 at the upper edge thereof as shown. An outer cylindrical baffle 26 preferably surrounds the coil O between the outer section 22 and the cylindrical wall of the evaporator chamber E. The baffles 24 and 26 serve to confine the liquid refrigerant introduced to the evaporator chamber to the portion of the chamber occupied by the coil O.

Liquefied refrigerant from the chamber 11 is conducted into the evaporator chamber E by the pipe 12 which is sealed through an opening in the lower end wall 17 of the evaporator. In accordance with the invention, the expansion valve of the system is disposed within and arranged to discharge liquid refrigerant directly into the interior of the evaporator chamber E. The expansion valve proper may be supported by any suitable means and as shown, a circular supporting plate 27 carried by posts 28 fixed to the upper end wall 16 is provided for this purpose.

The expansion valve is located within and preferably axially of the liquid cooling coil O. The valve structure, as best shown in Figure 2, comprises a hollow valve body 29 having a central bore 30 carrying a slidable plunger 31. The plunger 31 is pressed upwardly by a spring 32 carried in a central recess 33 in the plunger and compressed between the plunger and a shoulder 34 in the central bore 30 of the body 29. The recess 33 in the plunger 31 is connected through the transverse passages 42 to a valve chamber 43 surrounding the upper end of the plunger. The upper end of the plunger 31 is provided with a shallow circular recess carrying a valve member comprising a thin circular disc 44. The upper end of the valve body 29 is closed by a plug 45 having a central discharge orifice 46 therethrough. Annular valve seats 47 are formed on the lower surface of the plug 45 about the orifice 46 for engagement by the valve member or disc 44 when the valve is closed. A valve operating rod 48 passes loosely through the orifice 46 and is engageable with the center of the disc 44. The liquefied refrigerant pipe 12 is suitably connected to the central bore 30 of the expansion valve body 29 by a union 49.

From the description given, it will be apparent that when the operating rod 48 is pressed inwardly through the orifice 46, the disc 44 is moved from its seat 47 against the resistance of the spring 32, and liquid refrigerant flows out through the orifice 46 along the surface of the operating rod 48.

The expansion valve is preferably operated to admit liquid refrigerant to the evaporator chamber E by the expansion of a pressure expansible chamber and the pressure in this chamber is varied in accordance with changes in the evaporator chamber. In the disclosed embodiment, the temperature responsive element in the evaporator chamber comprises a bulb 50 disposed about a portion of the inner section 23 of the liquid coil O, and is thus responsive to the temperature of the coil and the temperature of the interior of the evaporator chamber E. The bulb 50 carries a suitable thermally expansible fluid which may be in gaseous form or may be partly in liquid form and partly gaseous. For the purpose of illustration, a body of readily volatilizable liquid 51 has been shown in the bulb 50.

In accordance with the invention, it is preferred to isolate the pressure expansible valve operating chamber from the interior of the evaporator chamber, while locating the expansion valve proper within the evaporator chamber. The purpose of isolating the expansible pressure chamber from the evaporator is to maintain the pressure chamber at a higher temperature than the maximum temperature to which the bulb 50 is subjected during operation of the system, thus maintaining proper control of the refrigerant flow. If the expansible pressure chamber was at any time reduced to a temperature below that of the bulb, the pressure expansible fluid would condense and/or contract in the pressure chamber 65 and thus counteract the expansion of such fluid in the bulb, and erratic control operation with wide temperature variations would result.

The pressure expansible valve operating chamber may be isolated from the interior of the evaporator chamber in various ways. Thus, as shown in Figure 1, the pressure chamber may be formed within an end wall 16 of the evaporator chamber E, and since with the refrigerating system in operation, the interior of the evaporator 75

chamber and the liquid coil O therein are at all times cooler than the surrounding atmosphere, the pressure chamber in the evaporator wall will be warmer than the bulb 50.

5 The pressure expandible chamber may be made in various ways and in general, comprises a sealed cavity having a flexible or movable wall such as a flexible diaphragm, an expansible bellows or the like. As shown in Figure 1, a central recess is 10 formed in the inner surface of the evaporator end wall 16 and a flexible diaphragm 53 is disposed in spaced relation to the inner face of this recess, thus defining a pressure chamber 54. The pressure chamber 54 and diaphragm 53 are isolated 15 from the interior of the evaporator chamber E by a plate 52 which also serves to seal the diaphragm in place. The plate 52 may be sealed within the recess in the wall 16 by suitable means such as solder, as indicated at 55. The bulb 50 20 is connected to the pressure chamber 54 by a pipe 56 which passes through the wall 16 and communicates with the chamber 54 through an opening 57 in the wall 16 as shown. A sealed charging tube 58 communicates with the pressure 25 chamber 54 through the wall 16. The movement of the flexible diaphragm 53 in response to pressure changes in the chamber 54 is transmitted to the operating rod 48 of the expansion valve by a plunger 59 slidably carried in a central opening 30 through the plate 52.

In accordance with the invention, means are provided on the valve operating mechanism for deflecting the stream of liquid refrigerant discharged from the valve orifice 46 into a spray which comes into direct contact with the liquid coil O or other body or surface to be cooled.

Thus, as best shown in Figure 2, a deflector 60 is attached to or formed integral with the operating rod 48 and extends radially outward therefrom. The deflector 60 may comprise an integral part with the plunger 59 or may be suitably secured thereto as desired. The lower face of the deflector 60 is preferably concave or dished as shown at 61. With this arrangement, the liquid 45 refrigerant stream flowing along the rod 48 when the expansion valve is open strikes the concave end surface 61 of the deflector 60 and is sprayed radially outward in a spray which impinges directly on the surrounding coil O. The path taken 50 by the liquid refrigerant is indicated by the arrows in Figure 2.

The deflector 60 not only serves as an effective means for breaking up the liquid refrigerant and directing it against the liquid coil, but also aids 55 in properly closing the expansion valve. Thus when the pressure within the chamber 54 drops to a predetermined point, due to a drop in the temperature of the bulb 50 to a value slightly above the minimum value required, the spring 32 60 and the reaction of the liquid refrigerant impinging on the deflector 60 combine to move the operating rod 48 upwardly, and the valve disc 44 is seated to cut off the flow of liquid refrigerant. When the valve disc 44 is seated, the force of the 65 impinging refrigerant is no longer applied to the operating rod, but the continued reduction in temperature of the evaporator, due to the continued evaporation of refrigerant therein while the 70 valve moves to its closed position, reduces the pressure in the chamber 54 to a value below that capable of reopening the valve against the resistance of the spring 32. Thus the expansion valve starts to close just before sufficient refrigerant 75 has been admitted to the evaporator chamber, and

the admission of excess quantities of refrigerant to the evaporator is avoided.

It is usually preferred to employ a pressure regulating valve in the evaporator suction line to aid in maintaining a substantially constant temperature in the evaporator chamber E and such a valve is shown at P in the pipe 9. The valve P may be of any suitable construction capable of maintaining a substantially constant pressure in the evaporator E. As shown, the valve member 34 of the valve P is operated by a bellows 35 exposed on one side to the pressure in the evaporator E and on the other side to atmospheric pressure and the pressure of a variably adjusted spring 36. The spring pressure may be varied by 10 rotation of the threaded sleeve 37 which raises or lowers a spring abutting nut 38, held against rotation with the sleeve 37 by a rod 39. A central threaded stem 40 is provided for closing the valve when the system is not in use, and the spring 20 adjusting sleeve 37 is held against accidental movement by a lock nut 41. With the arrangement described, an increase in pressure in the evaporator chamber beyond a predetermined point compresses the bellows 35 against the spring 25 36 and so opens the valve 34 and permits the escape of sufficient refrigerant gas to lower the evaporator pressure to the desired point.

In a modified form of the invention shown in Figure 4, the pressure expandible chamber which 30 operates the expansion valve is located outside of the wall of the evaporator chamber. Thus the upper end wall 16' carries a centrally apertured fitting 62 threaded or otherwise suitably sealed in a central opening through the wall 16' as 35 shown. A cap 63 having an annular recess 64 therein extends over the edges of the outwardly extending flange 65 on the fitting 62, and a flexible diaphragm 66 is disposed between the edges of the flange 65 and the cap 63. The sealed joint 40 67 of solder or the like unites the cap 63, the flange 65 and the diaphragm 66. The annular recess 64 forms a pressure expandible chamber between the cap 63 and the diaphragm 66, and a pipe 56' connects this chamber with the bulb 50 within 45 the evaporator chamber. A sealed charging tube 68 may be provided for the pressure chamber 64. The diaphragm 66 acts on a plunger 69 slidably supported in the central aperture through the fitting 62, and the lower end of this plunger is 50 suitably connected to the deflector 60' and the valve operating rod 48' within the evaporator chamber. The rod 48' operates the expansion valve in the manner described above in connection with Figures 1 and 2.

55 In the operation of the disclosed embodiments of the invention, the inlet 19 of the coil O is connected to a source of the liquid to be cooled and the refrigerant compressor 5 is started. Liquefied refrigerant collects in the chamber 11 and is delivered to the evaporator chamber E through the pipe 12, the expansion valve being open at this point due to the comparatively high temperature in the evaporator chamber. The liquefied refrigerant is sprayed on to the coil O by the deflector 60 of the expansion valve mechanism, and this refrigerant evaporates as it passes down over the coil O between the baffles 24 and 26. The evaporated refrigerant is withdrawn from the evaporator chamber E through the suction 65 line 9. The evaporation of the liquid refrigerant cools the coil O and when the desired low temperature has been obtained, the pressure in the evaporator chamber E falls to the point where the valve P closes. As the evaporator tempera- 70 75

- ture approaches the desired minimum temperature, but before this temperature is reached, the contraction or condensation of the thermally sensitive fluid 51 in the bulb 50 results in the closing of the expansion valve in the manner described above. The evaporation of the remaining liquefied refrigerant in the evaporator chamber reduces the evaporator temperature to the desired low point at which the valve P closes.
- 10 When the valve P is closed, the pressure in the suction line 9 is quickly reduced by the compressor 5 to a point where the pressure operated switch S opens and stops the compressor.
- When the cooled liquid is drawn from the coil
- 15 O, the uncooled liquid advancing through this coil heats the bulb 50, expands and/or evaporates the thermally sensitive fluid 51 therein and thus opens the expansion valve and admits liquefied refrigerant to the evaporator chamber E.
- 20 The evaporation of this liquid cools the coil O to the desired temperature, and the expansion valve is again closed, as explained above. The suction line valve P opens to permit the flow of evaporated refrigerant until the desired low temperature is reached. Whenever the pressure in the
- 25 suction line 9 rises above a predetermined value, the switch S is closed and the refrigerant compressing and condensing apparatus operates to replenish the supply of liquefied refrigerant in
- 30 the chamber 11.

Although the invention has been described in connection with a draft liquid cooler, it should be understood that the invention is not limited to this application and that the improved expansion and evaporating means may be employed in the usual refrigerator cooling units and generally in systems for cooling any body, surface, fluid or space.

I claim:

- 40 1. A refrigerating expansion device comprising a hollow valve body, a plunger slidable in the

body, a spring acting to force the plunger upwardly, the upper end of the plunger being provided with a shallow circular recess, and a valve member comprising a thin circular disc in the recess.

2. A refrigerating expansion device comprising a hollow valve body, a plunger slidable in the body, a spring acting to force the plunger upwardly, the upper end of the plunger being provided with a shallow circular recess, and a valve member comprising a thin circular disc in the recess, together with a plug closing the upper end of the valve body, said plug having a central discharge orifice therethrough.

3. A refrigerating expansion device comprising a hollow valve body, a plunger slidable in the body, a spring acting to force the plunger upwardly, the upper end of the plunger being provided with a shallow circular recess, and a valve member comprising a thin circular disc in the recess, together with a plug closing the upper end of the valve body, said plug having a central discharge orifice therethrough, an annular valve seat formed on the lower surface of the plug about said orifice for engagement by the valve member when the valve is closed.

4. A refrigerating expansion device comprising a hollow valve body, a plunger slidable in the body, a spring acting to force the plunger upwardly, the upper end of the plunger being provided with a shallow circular recess, and a valve member comprising a thin circular disc in the recess, together with a plug closing the upper end of the valve body, said plug having a central discharge orifice therethrough, an annular valve seat formed on the lower surface of the plug about said orifice for engagement by the valve member when the valve is closed, and a valve operating rod passing loosely through the orifice and engageable with the center of the disc.

ANTHONY T. STOCK.
